[57] CLAIM

The ornamental design for a stay bar bracket for single glider window, as shown and described.

DESCRIPTION

FIG. 1: is a front perspective view of a stay bar bracket for single glider window showing our new design;

FIG. 2: is a rear elevational view of the stay bar bracket of FIG. 1;

FIG. 3: is a top plan view of the stay bar bracket of FIG. 1; and,

FIG. 4: is a left side elevational view of the stay bar bracket of FIG. 1, the right side elevational view being a mirror image thereof.
